UNITED STATES PATENT OFFICE.

WILLIAM O. PARSONS, OF INDIANAPOLIS, INDIANA.

JOURNAL-JACK.

1,132,114.

Specification of Letters Patent. Patented Mar. 16, 1915.

Application filed June 17, 1914. Serial No. 845,611.

To all whom it may concern:

Be it known that I, WILLIAM O. PARSONS, a citizen of the United States, residing at Indianapolis, in the county of Marion and 5 State of Indiana, have invented certain new and useful Improvements in Journal-Jacks, of which the following is a specification.

This invention relates to journal jacks for lifting the journal boxes of car wheels 10 during the process of removing the brasses therefrom, and more particularly relates to an improved means for maintaining the jack pawl at any desired angular relation with the jack base in such position as to 15 positively engage the wheel flange for maintaining the wheel upon the rail while jacking up the journal box.

One of the principal objects of the invention is to provide an improved wedge or 20 block inseparably connected with the jack and adapted to coact with the jack base and pawl for positively holding the latter in engagement with the wheel flange, and further adapted to provide a solid backing between the pawl and jack to form a medium 25 for the thrust occurring incident to the jacking process.

Another object of the invention is to provide a device of the class described including a substantially arcuate wedge having a toothed surface adapted to coact with the toothed bearing portion of the jack pawl in 30 positioning the wedge relatively to the pawl and jack base for maintaining the former in adjusted position in contact with the wheel flange.

A further object is to provide in combination with a jack having a pivoted pawl, a toothed wedge adapted to maintain the pawl 40 in adjusted position, the wedge being provided with means, in the form of a retaining ring surrounding the pivot pin, for preventing accidental loss of the wedge and adapted to always maintain the latter in 45 accessible position to the person operating the jack.

Still another object of the invention is to provide a device of the type specified, which will be extremely simple, durable, efficient 50 in operation and inexpensive to manufacture.

With these and other objects in view, which will become apparent as the description proceeds, the invention resides in the 55 construction, combination, and arrangement of parts hereinafter more fully described

and claimed, and illustrated in the accompanying drawing, in which like characters of reference indicate like parts through the several figures, of which,

Figure 1 represents a side elevation view, partly in section, of a jack constructed according to my invention, illustrating the same in operation. Fig. 2 represents a top plan view thereof, partly in section. Fig. 3 65 represents a perspective view of the wedge, turned upside down, and Fig. 4 represents a transverse sectional view taken through the pawl, on the plane indicated by the line 4-4 of Fig. 2.

Referring more particularly to the drawing, the jack includes the base 5 carrying the jack screw 6 having a corrugated head 7 adapted to engage beneath the journal box of a car for lifting the same, the jack screw 75 being operable by the usual form of pawl and ratchet mechanism indicated generally at 8.

Base 5 is provided with an upper beaded edge 9 beveled for a portion of its circumference as at 10, and adjacent the beveled portion and disposed one on each side thereof on the opposite side of the jack from the handle 11 is a pair of parallel ears or lugs 12.

The pawl 13 is substantially wedge shaped, 85 curving downwardly toward its outer end or nose portion 14, and is substantially in the form of an I beam in cross section as indicated in Fig. 4, and at its rear end is bifurcated to provide spaced ears 15 adapted to 90 be positioned between, and to be swiveled to the ears in a manner to allow vertical adjustment of the pawl, by a pivot pin 16 disposed centrally of ears 12 and 15. The outer edge of the pawl ears are rounded as at 17, 95 and on their upper periphery adjacent the jack are provided with transversely disposed teeth 18.

The wedge 19 is substantially arcuate in formation and tapers toward its nose 20 100 and is of a longitudinal curvature substantially equal to the curvature of the pawl ears, and is provided with a preferably integral retaining ring 21 depending centrally from its under surface and disposed in a 105 place coincident with the longitudinal medial line of the wedge, said ring being connected to the wedge by a short shank 22. The ring is of a greater inside diameter than the diameter of pin 16, and through said 110 ring the pin is adapted to be extended, in assembling the device, whereby the wedge

will always be retained in an accessible position to the operator. The under face of the wedge at its central position and on each side of the shank 22 is provided with transversely disposed teeth 23 adapted to engage with the teeth 18 on each pawl ear, in maintaining the wedge in any adjusted position relatively to the pawl. A finger hold in the form of an eye 24 extends from the base 10 end of the wedge, and serves as means for the ready manipulation of the wedge.

By reason of the loose connection between the wedge and pawl, the former may readily be lifted out of engagement with the 15 pawl ears during the process of adjusting the pawl, and may be swung toward the jack base into engagement with the beveled portion 10 of the jack and then engaged with the teeth on the pawl ears, and when in this 20 position, as will readily be understood, will positively maintain the pawl in engagement with the wheel flange in the manner indicated in the drawing, and will prevent upward movement of the pawl relatively to 25 the jack during the process of jacking up the hot box, and hence resulting in the maintenance of the car wheel on the rail so that the box may be lifted sufficiently to allow the loosening and removal of the brasses.

30 Although I have described the preferred embodiment of my invention, I may desire to make such changes in the construction combination, and arrangement of parts thereof, as do not depart from the spirit of the invention and the scope of the appended claims.

I claim:

1. A device of the class described, comprising a jack having a beveled portion on 40 its base, spaced ears provided on the jack, a pawl having spaced ears on its rear end, the pawl ears being disposed between the jack ears, a pivot pin extending through the ears for pivoting the pawl relatively to the jack, 45 said pawl ears being rounded and provided with transversely disposed teeth, a wedge having a ring depending centrally from its under face and loosely surrounding the pivot pin, said wedge being of a longitudinal curvature 50 substantially equal to the curvature of the pawl ears, said wedge having transversely disposed teeth provided on its under

face and adapted to coact with the teeth on the pawl ears in maintaining said wedge in adjusted position relatively to the pawl, said wedge adapted to be brought into engagement with the beveled jack portion for maintaining the pawl in adjusted position relatively to the jack. 55

2. A device of the class described, comprising a jack having a beveled portion, a pin carried by the jack, a pawl pivoted on said pin and provided with a toothed portion, a wedge loosely connected with the pin and adapted to be brought into engagement 60 with and between the toothed portion of the pawl and the beveled portion of the jack, said wedge provided with teeth adapted to coact with the toothed portion of the pawl whereby to maintain the pawl in adjusted 65 position relatively to the jack. 70

3. A device of the class described, comprising a jack having a pawl adjustably connected therewith, a wedge adjustably connected with the pawl and adapted to be positioned between the pawl and jack, and coacting interlocking means between the wedge and pawl for maintaining the former in adjusted position relatively to the latter. 75

4. The combination with a jack having an 80 adjustable pawl, of a wedge, means for irremovably and adjustably connecting the wedge and pawl, and coacting interlocking means for maintaining the former in adjusted position relatively to the latter. 85

5. A device of the class described including a wedge, said wedge being provided with a retaining ring extending from one side thereof, and being further provided with teeth on one side thereof, and a finger hold 90 carried by the wedge. 90

6. A device of the class described, including a pawl, a jack, a pin for pivoting the pawl relatively to the jack, a wedge adapted to be interlocked between the pawl and jack, 95 and a ring carried by the wedge and loosely surrounding the pin.

In testimony whereof I affix my signature in presence of two witnesses.

WILLIAM O. PARSONS.
